Primary Examiner — Cynthia M. Chin(74) *Attorney, Agent, or Firm* — ScienBiziP, P.C.(57) **CLAIM**

The ornamental design for a toy gun, as shown and described.

DESCRIPTION

FIG. 1 is a front, right, and top perspective view of a toy gun, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view taken from FIG. 1 showing protrusions on the magazine of the toy gun.

FIG. 10 is a partial enlarged view taken from FIG. 1 showing a decorative board on the side of the toy gun.

FIG. 11 is a partial enlarged view taken from FIG. 1 showing buttons on the scope of the toy gun; and,

FIG. 12 is a partial enlarged view taken from FIG. 2 showing the grip of the toy gun.

The dash-dot broken lines represent the boundaries of the enlarged partial views of FIGS. 9-12. All other broken lines represent portions of the toy gun that form no part of the claimed design. None of the broken lines form a part of the claim.
